EDGE-SETTING MACHINE

Laurence Elmer Topham, Boston, Mass., assignor
to United Shoe Machinery Corporation, Borough
of Flemington, N. J., a corporation of New
Jersey

Application February 28, 1938, Serial No. 193,036

19 Claims. (Cl. 12—78)

This invention relates to machines for operating upon shoes and is illustrated as embodied in a machine for burnishing or setting the edges of soles.

In edge-setting machines, for example, the operating mechanism for the edge-setting tools sets up vibrations of considerable amplitude, and the transmission of these vibrations from the operating mechanism to the machine frame is the cause of much noise as well as destructive wear upon the machine. Accordingly, it is an object of this invention to reduce the amplitude of the vibrations transmitted from the operating mechanism to the machine frame. In the illustrated machine, this result is obtained by the use of resilient connecting means located between the machine frame and the operating mechanism for the edge-setting tools, which is arranged to hold the operating mechanism spaced from the machine frame, and at the same time to absorb a part of the vibrations given off by the operating mechanism. Yieldingly supporting the operating mechanism in spaced relation to the machine frame is especially advantageous in edge-setting machines because, in addition to absorbing vibrations, the yielding support permits the operating mechanism together with the attached edge-setting tools to move relatively to the machine frame, thus facilitating the edge-setting operations upon sharply curved portions of the shoe soles such as the toe portions.

Edge-setting machines heretofore available operate at relatively low speeds ranging from approximately 3450 to 3500 oscillations of the tool shaft a minute, and, while generally satisfactory when operated at these speeds, the machines have a tendency to produce streaks of different brilliancy on the sole edge operated upon and the operator has difficulty in setting the abruptly curved portions of the sole edge. While these machines are mechanically capable of operating at higher speeds, such high speed operation is not practicable due to the excessive amount of vibration and noise which occurs at the higher speeds. The excessive vibration is due to a number of different causes, a very prominent one of which is the intense vibration of the operating mechanism beyond low critical speeds. With this in view, it is another important object of this invention to provide an improved edge-setting machine capable of operating smoothly and quietly at operating speeds in the neighborhood of 6000 oscillations a minute and as an aid in the accomplishment of this object, to provide an operating mechanism which is not subject to a

low critical speed. To this end a feature of the present invention resides in an improved operating mechanism embodying a rotatable operating member which, as illustrated herein, is so constructed and arranged that the stresses set up in the member when rotated tend to bend it in opposite directions with a resulting balancing effect whereas if these stresses tended to bend different portions of the member in the same direction there would be an unbalancing effect. Preferably, and as illustrated herein, the rotatable member consists of a rotary shaft with parallel crank members extending from the ends thereof, the arrangement being such that when the shaft is rotated, deflection of the crank members, due to the resiliency of the material out of which they are constructed, will tend to bend the shaft into a shape resembling a relatively flat sine curve, thus maintaining the center of gravity of the rotating shaft substantially constant, thereby avoiding low critical speeds and the attendant violent vibrations.

In the edge-setting machine illustrated herein, the hollow shank or spindle in the tool-carrying head which may be turned to bring one or the other edge-setting tools into operative position is retained within the tool shaft by a connecting pin which is rotatably mounted within the shaft, the inner end of the pin being located adjacent to the connection between the tool shaft and the operating crank. The connection between the pin and spindle is made by means of a cap attached to one end of the pin and a spring interposed between the cap and spindle, the cap being attached to the spindle by a sliding and turning movement. According to another feature of this invention, provision is made for preventing the connecting pin from rotating while the cap is being attached to the end of the pin to hold the turret assembly in place. To this end, means are provided within the casing and adjacent to the inner end of the pin which are arranged for holding engagement with the pin when the cap is being placed on or taken off of the pin.

Invention is also to be recognized in the provision of relatively heavy casings for the operating mechanism which themselves absorb a considerable amount of the reaction of the operating mechanism and thus decrease the extent of the vibration transmitted to the support, and also in the construction of the casing and the arrangement of the lubricating system which makes it possible for the lubricating system to apply a lubricant to the connections between the oper-

ating mechanism and the tool shafts which are located within the casing.

With the above and other objects in view, the invention will now be described with reference 5 to the accompanying drawings and will be pointed out in the appended claims.

In the drawings:

Fig. 1 is a plan view of the edge-setting machine with the cover plates removed and parts of 10 the machine in section;

Fig. 2 is a side view, partly in section, the sectional portion of the view being taken along the line II—II of Fig. 4, of the machine shown in Fig. 1;

15 Fig. 3 is an elevation of the right end of the machine shown in Fig. 1, with the end of the housing and cover plate broken away;

Fig. 4 is a sectional view taken along line 20 IV—IV of Fig. 1 but on a larger scale and with the housing omitted for purposes of clarity;

Fig. 5 is an exploded perspective view of a portion of the pin and cap assembly which holds the tool head shank in the tool shaft; and

25 Fig. 6 is a schematic representation of the crank mechanism for operating the tool shafts as viewed from the side.

The illustrated machine comprises a frame which consists of a standard 10 supporting a head which comprises a pair of housings 12, 14 30 which enclose the actuating mechanism of the machine. Removable cover plates 16, 18 (Fig. 2) and support plates 20, 22 (Fig. 1) complete the closure of the housings. The actuating mechanism of the machine comprises a rotary drive shaft 24 (Fig. 1) from the ends of which extend crank members 26, 28, which are parallel to each other and extend at an angle to the axis of the driving shaft. Attached to the driving shaft 24 is a pulley 30 which is operated by a belt 32. The 40 crank members 26, 28 are connected to parallel tool shafts 34, 36, in a manner which will herein-after be described, the connection between these cranks and tool shafts constituting the sole supporting means for the drive shaft 24 and the 45 cranks.

Enclosing the tool shafts and cranks are heavy casings 38, 40 which form the bearings for the tool shafts and which, due to their mass, absorb a considerable amount of the reaction of the operating mechanism. These casings are maintained in spaced relation to the sides of the housings 12, 14 by means of springs later to be described which allow the casings together with the mechanism enclosed therein to move relatively to the walls of the housings, and at the same time absorb a portion of the vibrations set up by the operating mechanism located within the casings and thus further reduce the amplitude of the vibrations which are transmitted to the supporting portions of the housings. The 55 structural arrangement of the machine parts is the same in both housings, consequently it will suffice to describe in detail one set of machine parts, such for example, as would be located in the right housing as viewed in Fig. 1. Similar parts hereinafter described will be given like numerals in both housings.

The vertical support for the casing 38 is provided by three relatively heavy springs 42, 44, 46 70 which are seated upon lugs formed on the base of housing 14 (Fig. 2) and which extend upwardly through openings in the casing and into engagement with recesses in a casing head 76 (Fig. 4). The rear portion of the casing is spaced from the adjacent wall of the housing by four springs

48, 50, 52, 54 (Fig. 2) which converge inwardly from recesses formed in the adjacent wall of the housing and into seating engagement with inclined spring seats formed in the rear wall of the casing 38 (Figs. 1 and 2). The front of the casing provides the bearing for the tool shaft 34 and is formed with a projecting portion 39 which extends outwardly through an opening in the supporting plate 20 (Fig. 1). This projecting portion of the casing is spaced from the walls of the opening in the supporting plate 20 by a pair of vertically arranged springs 56, 58 (Figs. 2, 3 and 4) interposed between spring seats formed in the projecting portion 39 of the casing and supporting plates 60, 62 which are attached to lugs 64 struck out from the front wall of the supporting plate 20 (Fig. 3), and by a pair of horizontally extending springs 66, 68 (Fig. 1) interspaced between inclined flanges 70, 72 extending outwardly from the front wall of the supporting plate 20 and inclined spring seats formed in the adjacent sides of the projecting portion 39 of the casing (Fig. 1).

5 Casing 38 comprises a base section 74 and a head section 76 (Fig. 3) which is clamped to the base section by bolts 79. The base section is provided with a longitudinal recess 83 (Fig. 1) arranged to receive the actuating crank 26, and with a transverse aperture extending through the projecting portion 39 of the casing and opening 80 on to the recess 83 for the reception of the tool shaft 34. To facilitate the assembly of the actuating mechanism in the casing, the projecting portion 39 of the casing is made in two sections (Figs. 2 and 3), an upper section 77 and a lower section 78 which are fastened together by bolts 80. When assembling the actuating mechanism in the casing, the head section 76 and the upper section 77 of the base 74 are removed and the actuating mechanism inserted in the lower section 78 of the base, with the tool shaft seated in that portion of the aperture formed in the lower section, after which the upper section 77 is bolted to the lower section 78 and the head section 76 is fastened to the assembled base.

Surrounding the crank 26 (Fig. 1) and spaced therefrom by ball bearings 81, is a sleeve 82 having oppositely extending trunnions 86, 88 (Fig. 4) which are rotatably mounted in a hub 90 on the tool shaft 34. The hub 90 (Fig. 4) comprises a lower arm having an opening therein which receives the lower trunnion 88 and an upper arm 84 (Figs. 1 and 4) which is bolted to a yoke 91 fitted around the upper trunnion 86.

As illustrated in Fig. 1 and shown in the schematic representation of Fig. 6 in which the angular relation between the crank members 26, 28 and the shaft 24 is exaggerated somewhat for the purpose of clarity, the axis 92 of the driving shaft 24 intersects the axis of the tool shaft 34 (Fig. 1) and the axis 94 of the crank 26 which extends at an angle to the axis 92 of the driving shaft intersects the latter at its point of intersection with the axis of the tool shaft, thus rotation of the driving shaft will cause the crank to gyrate about the point of intersection of the three axes as a center in such a manner as to generate a double cone the vertex of which is at said point. In this manner the sleeve 82 is caused to gyrate in consonance with the crank and is given a characteristic movement which may be resolved into two components, the first component being movement in a horizontal plane parallel to the axis of the tool shaft, which serves merely to rotate the sleeve 82 back and forth in the hub 76.

90, the second component being movement in a vertical plane perpendicular to the axis of the tool shaft, which is effective to oscillate the tool-carrying shaft through the agency of the hub 90. The mechanism for translating gyroscopic motion of the crank into oscillatory motion of the tool shaft is duplicated between the opposite crank 28 and its associated tool shaft 36.

Rotation of the drive shaft 24 will cause the 10 tool shafts 34, 36 to move simultaneously in the same direction due to the parallel arrangements of the cranks 26, 28, and the resistance by the tool shafts to this motion will cause reverse stresses to be set up in the shaft 24 due to the 15 fact that the reactions from the tool shafts occur at opposite sides of this shaft. These reactions from the tool shaft will cause a slight amount of bending in the cranks due to the elasticity of materials out of which they are made. However, as 20 the cranks are on opposite sides of the shaft 24 and are parallel to each other, the unbalancing effects resulting from the bending of these cranks offset each other, thus maintaining the center of gravity of the rotating mass substantially constant, thereby avoiding a low, critical speed with 25 its attendant violent vibrations. Stated in another manner, the internal strains set up in the crank shaft due to the parallel arrangement of the cranks tend to bend it in an S-shape, or into 30 the shape of a flat sine curve. This will result in such a symmetrical deformation of the shaft about its axis of rotation as will not seriously disturb the center of gravity of the rotating shaft.

The shaft 24 and the cranks, 26, 28 are in a 35 state of static balance, but, due to the use of the spaced bearings 81 (Fig. 1) which apply loads to these cranks at unequal distances from the pulley 30, the cranks are not in a condition of dynamic balance. To restore a condition of dynamic balance counterweights 134 are attached to the ends 40 of these cranks.

Extending outwardly from the tool shaft hub 90 (Fig. 4) is a tool shaft 34 which is recessed near its inner end to receive a bearing 94 for a 45 rotatable connecting pin 96. The connecting pin 96 is provided with an enlarged head 98 at its inner end which normally engages the bearing 94 and limits the outward movement of the pin. The head 98 is provided with a recess 100 which 50 is arranged to engage a lug 102 (Figs. 1 and 4) on the adjacent face of the crank sleeve 82 under certain conditions which will be hereinafter described. Slidably and rotatably received within the tool shaft 34 is a hollow shank or spindle 104 extending laterally from a tool carrying head 106 which is provided with interchangeable edge-setting tools 106a and 106b (Fig. 3) either of 55 which may be brought into operative position by giving the tool head and spindle a half rotation with respect to the tool shaft 34. The wall of the shank 104 is located between the wall of the tool shaft 34 and the connecting pin 96 and at 60 its inner end is provided with an inturned flange 108 which forms an opening through which the pin 96 extends. The tool head shank is retained within the tool shaft by a cap 110 attached to the outer end of the connecting pin 96, the cap compressing a spring 122 between its lower face and the inturned flange 108, thus resiliently urging 65 the tool head into seating engagement with the tool shaft. The cap 110 has formed therein a bore which extends inwardly from one end, the diameter of the bore being slightly greater than the length of the elongated head 124 on the pin 96. The bore is connected with the other end

of the cap 110 by a slot 114 which is slightly wider than the widthwise dimension of the head 124, but which is not as wide as the lengthwise dimension of the head. The end faces of the slot 114 are provided with recesses 116 for locking engagement with the under surface of the head 124. Threaded into the opening in the shank 104 is a plug 92 which seals this opening and thus prevents the escape of oil which would otherwise work its way out through this passage 10 from the interior of the casing. The tool head is assembled in the following manner. The shank portion 104 is first inserted into the opening in the tool shaft 34, the opening formed by the flange 108 fitting over and sliding along the pin 15 96. After the shank has been fully inserted in the tool shaft the spring 122 is then slid over the pin 96 and the cap 110 is first pressed inwardly, by a tool, not shown, compressing the spring 122 and moving the pin 96 inwardly until 20 the recess 100 in the head 98 engages the lug 102 on the crank sleeve, thus holding the pin 96 against rotation. The cap is then rotated through an angle of 90° and is allowed to move outwardly under the urging of the spring 122, 25 which movement will cause the pin head 124 to seat in recesses 116 in the cap, thus locking the cap in engagement with the head of the connecting pin and maintaining the spring 122 under compression to retain thereby the tool head shank 30 104 within the tool shaft. When pressure is removed from the cap 110 the spring 122 will move the cap and pin 96 outwardly causing the head 98 to move out of engagement with the lug 102 and into engagement with the bearing 94. 35 The construction of the tool head 106 and the shifting mechanism for rotating this tool head form no part of this invention, that mechanism forming part of the subject-matter of the application for United States Letters Patent Serial No. 175,293, filed November 18, 1937, in the name of William Hamann.

In order that the connections between the tool shaft and the crank may be properly lubricated, the casing head 76 is provided with a central opening 126 (Figs. 1 and 4) disposed above these connections, and has attached thereto, adjacent its outer end, an inclined trough 128 arranged to discharge a lubricant through the opening 126 onto the connections between the crank and tool shaft. Mounted on the end of the crank is an oil chain 130 which carries the oil up from the bottom of the chamber and throws it against an inclined baffle plate 131 (Fig. 2) which in turn delivers it to the trough 128. To prevent the escape of oil from the chambers through the openings formed therein for the reception of the drive shaft 24 and pulley 30, baffles 132 are provided which depend from the cover plates (best shown in Figs. 1 and 2) and substantially close 60 these openings. A gasket 136 (Figs. 1 and 4) fills the space between the projecting portion 39 and the plate 20 for a similar purpose.

Having thus described my invention, what I claim as new and desire to secure by Letters Patent of the United States is:

1. An edge-setting machine having, in combination, an oscillatable tool shaft, operating mechanism for the tool shaft, a support, and yieldable means for mounting said shaft and 70 operating mechanism on the support whereby the amplitude of the vibration transmitted to the support and the noise caused by vibration is minimized.

2. A machine for operating upon shoes hav- 75

ing, in combination, a casing, a tool shaft and operating mechanism therefor disposed within said casing, a support, and resilient means interposed between the support and the casing 5 for sustaining the casing, the casing and resilient means absorbing vibration set up by the tool shaft and its operating mechanism thereby reducing the amplitude of the vibration transmitted to the support.

10 3. An edge-setting machine adapted to operate at high speed having, in combination, an oscillatable tool shaft, a crank arranged to oscillate said tool shaft, a relatively heavy casing surrounding said crank and tool shaft, a base, and resilient means supporting the casing on 15 the base, the inertia of the casing and the yielding of the resilient means acting to dampen out vibration set up by the crank and thus reduce the amplitude of the vibration transmitted to 20 the base thereby enabling the machine to run quietly and smoothly at high speed.

4. A machine for operating upon shoes having, in combination, a support, a tool shaft, operating mechanism for the tool shaft, said shaft and operating mechanism being positioned within the support, and yieldable means for holding the shaft and operating mechanism in spaced relation to the support whereby the shaft and operating mechanism may be moved relatively to the 25 support when the shoes are being operated upon and the amplitude of the vibrations transmitted to the support will be reduced.

5. A machine for operating upon shoes having, in combination, a support, a casing constructed 30 and arranged to receive a tool shaft and mechanism for operating the shaft, a tool shaft and operating mechanism therefor mounted in said casing, said casing being positioned within the support, and resilient means for sustaining the 35 casing in spaced relation to the support whereby the casing, tool shaft and operating mechanism may be moved relatively to the support in response to pressure from the shoe being operated upon.

40 6. A finishing machine having, in combination, spaced tool shafts arranged to receive finishing tools, operating mechanism for said shafts, a support, and resilient supporting means for holding the shafts and operating mechanism in spaced relation to the support whereby they 45 may be moved relatively to the support under pressure from the work and thus facilitate the operation of the finishing tools upon the work.

7. A finishing machine having, in combination, spaced tool shafts arranged to have finishing 50 tools mounted thereon, driving means connected to and supported by said tool shafts, casings supporting said tool shafts and forming bearings for the same, a support, and yieldable means for holding said casings in spaced relation 55 to said support whereby the shafts may be moved relatively to one another and to the support thus facilitating the operation of the finishing tools upon the work and reducing the amplitude of the 60 vibrations transmitted to the support.

65 8. A finishing machine having, in combination, spaced tool shafts arranged to have finishing tools mounted thereon, means for operating said tool shafts, bearings for said shafts, a support, and resilient means for mounting each of 70 said bearings on the support and spacing the same from the support thereby permitting said bearings to move independently of one another in response to pressures exerted upon the shaft.

75 9. A machine for operating upon shoes hav-

ing, in combination, a support, a plurality of tool shafts, means for oscillating said tool shafts, said means comprising an operating member, parallel cranks operated by the operating member and connections between the cranks and the tool shafts, and resilient means for holding the tool shafts and the means for oscillating those shafts in spaced relation to the support.

10 10. A machine for operating upon shoes having, in combination, spaced parallel tool shafts, and means for oscillating said tool shafts, said means comprising a rotatable member and connections between the member and the tool shafts, the rotatable member including cranks so constructed and arranged that the internal strains 15 set up in the member upon rotation tend to bend it into a shape resembling a flat sine curve.

11. An edge-setting machine adapted to operate at high speeds having, in combination, spaced parallel tool shafts, means for oscillating the shafts, said means comprising a rotatable member and connections between the member and the shafts which both support the rotatable member and transmit motion from the rotatable member to the shafts, said rotatable member including cranks so constructed and arranged that the forces set up in the member upon rotation are substantially balanced between its supports thereby reducing vibrations and avoiding low 20 critical operating speeds.

12. An edge-setting machine adapted to operate at high speeds comprising, in combination, spaced parallel tool shafts, means for operating said shafts, said means comprising a rotatable shaft having parallel cranks extending from 25 diametrically opposite positions on its ends and connections between the cranks and the tool shafts which both support the shaft and cranks and transmit motion from the cranks to the tool shafts, the arrangement being such that upon operation of the machine deflection of the cranks tend to deform said shaft symmetrically with respect to its axis of rotation whereby its 30 center of gravity is maintained substantially constant.

13. An edge-setting machine adapted to operate at high speed having, in combination, spaced parallel tool shafts, a rotatable operating shaft located between the tool shafts, a crank extending from each end of the operating shaft, the longitudinal axes of the cranks being parallel to each other and extending at an angle to the longitudinal axis of the operating shaft, and connections between the cranks and the adjacent tool shafts for transmitting motion from the cranks 35 to the tool shafts.

14. A shoe finishing machine adapted to operate at high speed having, in combination, a housing, arranged to receive and retain a lubricant, a crank and a finishing tool shaft located within said housing, a vibration absorbing casing surrounding a portion of the crank and tool shaft including the connections between those members, said casing having an opening therein exposing the connection between the 40 crank and the finishing tool shaft, and means for carrying the lubricant from the lower portion of the housing for discharge through the opening in the casing and onto the connection between the crank and shaft lubricating the same.

45 15. A machine for operating upon shoes having, in combination, a casing, a tool shaft mounted in said casing, a tool holder, means for coupling the tool shaft with the tool holder comprising a rotatable member the inner end of which 50

is located within the casing and a cooperating member adapted for connection with the rotatable member, and means within said casing arranged for engagement with the rotatable member thereby preventing the same from rotating when the cooperating member and the rotatable member are being connected or disconnected.

16. A machine for operating upon shoes having, in combination, a casing, a tool shaft mounted in said casing, a tool holder, adjustable means for coupling the tool shaft with the tool holder comprising a member slidably and rotatably mounted in said tool shaft, the inner end of the member being located within the casing, said member being arranged to slide inwardly upon adjustment of the coupling means, and means within the casing arranged to engage said member upon its inward movement thereby preventing it from rotating while the coupling adjustment is being made.

17. In an edge-setting machine comprising a casing, a tool shaft mounted in said casing, and mechanism for operating the tool shaft located within said casing, the combination of a tool holder, disconnectable means for coupling the tool holder with the tool shaft comprising a member slidably and rotatably mounted on said tool shaft, the inner end of the member being posi-

tioned within the casing, said member being arranged to slide inwardly upon connection or disconnection of the coupling means, and means on said operating mechanism adapted for engagement with the member upon its inward movement thereby preventing it from rotating while the coupling adjustment is being made.

18. An edge-setting machine adapted to operate at high speeds having, in combination, a support, a tool-carrying shaft adapted to oscillate about a substantially horizontal axis, a drive shaft connected to said tool shaft to oscillate it, a massive casing surrounding the connection between said shafts, one of said shafts being journaled in said casing, and resilient means interposed between the casing and the support.

19. An edge-setting machine adapted to operate at high speeds having, in combination, oppositely directed, spaced, parallel tool shafts, means for supporting said shafts for oscillation about substantially horizontal axes, a drive shaft the axis of which intersects the axis of the tool shafts, parallel gyratory oblique cranks on said drive shaft adapted to gyrate about the intersection of said axes, and connections between the cranks and the tool shafts for oscillating the latter.

LAURENCE ELMER TOPHAM.
